TRIGGER MECHANISM

Paul Palé, Wilkes-Barre, Pa.

Application September 16, 1943, Serial No. 502,658

14 Claims. (Cl. 42—69)

This invention relates to trigger mechanism for firearms, and more particularly to such mechanism wherein a long trigger stroke is utilized and the point within the limits of the stroke at which the firing mechanism is tripped varies indeterminately and infinitely.

Modern firearms are designed to provide infinitesimal movement of the trigger from "cocked" to "tripped" position. Novices are taught by expert marksmen that the trigger must not be pulled but "squeezed" very gradually. In other words, the firing is not accomplished by moving the trigger through an appreciable arc, but rather by a gradual increase of pressure against the trigger until it suddenly trips and is free. To increase the safety factor, rules have been established for the majority of competitive meets which bar the use of any fire arm requiring less than a certain specified minimum trigger pressure to fire. This trigger action, light or heavy, presents many hazards to good marksmanship.

First, the gradual, smooth increase in pressure upon the trigger is difficult to attain, and to most persons comes only through long practice. Uneven or jerky increase in pressure will cause the gun to be deflected from the target and thus spoil the shot. Second, at the instant of release, the trigger mechanism is relieved of its load and the trigger moves freely. The pressure put upon the trigger to fire the gun causes the trigger to snap back quickly to its limit of movement. On those rare occasions, with modern ammunition, when a shell hangs fire for a brief interval, the sudden movement of the trigger after release will cause the gun to deflect and be off the target when the shell fires belatedly. Third, and most important, expert and experienced marksmen learn the action of their firearms after but a few shots so that they subconsciously know or sense the instant that the trigger is ready to release. Only a comparative few are so constituted that they can prevent a slight involuntary flinch in anticipation of the explosion to follow. This also spoils the aim. Even though the marksman becomes proficient in the operation of the trigger, he must learn to control his own reactions. He must keep his nerves under such rigid control that the human tendency to flinch in anticipation of the noise or shock will be overcome.

The object of this invention is to provide trigger mechanism which will overcome these mental as well as mechanical handicaps to good marksmanship by incorporating means to give a

long equalized trigger pull before and after release, and an indeterminate point of fire that varies infinitely within limits less than the full trigger stroke and is impossible to predetermine, so that a smooth trigger action is assured and the marksman can have no indication of when the firearm will fire.

Another object of the invention is to provide such mechanism which may be made as an attachment for stock firearms, the mechanism including an auxiliary trigger and accompanying mechanism to be secured to the firearm to actuate the existing trigger, or may be built into the gun as a part thereof and have a single trigger.

A further object of the invention is to provide in such a device means whereby the auxiliary trigger may be moved throughout its full range when the safety is on or the gun is jammed without damage to the firearm's mechanism or that of the attachment. It is also contemplated that in the event of failure of a portion of the mechanism in the attachment, an emergency firing of the gun may be accomplished by actual contact of the auxiliary trigger with the existing trigger if the trigger pull is continued.

The inventive concept includes means adapted to be applicable to any type trigger actuated firearm regardless of the trigger movement of the firearm as it is being cocked.

Broadly, the object of the present invention is to negative the probability of muzzle deflection during firing of the firearm by providing means to ensure smooth trigger operation and provide for an infinite number of points of fire so that the explosion will come as a surprise to avoid anticipation.

It is an object of the invention to provide means whereby an instructor may control the firing of the gun while standing far enough away to permit full freedom of movement and vision to the pupil.

Other objects of the invention will become apparent from the following specification taken in conjunction with the drawings which accompany and form a part of the specification and throughout the several figures of which the same characters of reference are used to denote identical parts throughout.

In the drawings:

Figure 1 is a side elevational view of an automatic pistol showing the invention in the form of an attachment;

Figure 2 is an enlarged side elevation of a por-

tion of a gun with the cover plate of the attachment removed;

Figure 3 is a view similar to Figure 2 showing parts in their position after the gun has fired and the trigger is on its return stroke;

Figure 4 is a vertical section taken on the line 4-4 of Figure 2;

Figure 5 is a horizontal section taken on the line 5-5 of Figure 2;

Figure 6 is a perspective view of the trigger 10 actuating unit;

Figure 7 is a detail view of a modified form of fulcrum cam actuating means;

Figure 8 is a view similar to Figure 2 showing the mechanism as adapted for use with a gun 15 having a different trigger movement;

Figure 9 is a perspective view of a gun showing remote control means for firing the gun;

Figure 10 is a fragmentary section through the case showing the modification necessary for 20 the use of remote control;

Figure 11 is a fragmentary section taken through the remote control means at right angles to the showing in Figure 10.

Referring to the drawings in detail and first adverting to that form of the invention shown in Figures 1 to 6, the invention is shown as applied to an automatic pistol 1. It is to be understood that the automatic pistol is merely illustrative of automatic guns in general, or any firearm having an equivalent trigger movement.

In Figures 1 to 6, the invention is in the form of an attachment 2 to be secured to the side of the gun by any appropriate means and in the most desirable position, on the gun illustrated, above and adjacent the trigger guard. It comprises a small case 3 having a base plate 4 and side walls 5. A cover plate 6 completes the case and protects the mechanism which the case houses.

Near the lower right hand corner of the case, as viewed in Figure 2, a stud 7 projects outwardly from the base plate to form a pivot for a trigger actuating plate 8. Preferably, although not necessarily, stud 7 is in axial alignment with the pivot for the trigger 9 of the gun. The trigger actuating plate 8 has a body portion 10 generally triangular in shape, and a depending trigger engaging arm 11 extending downwardly from the body portion adjacent the pivot 7. The trigger engaging arm passes through an opening 41 in the wall of the case and is offset laterally as at 12 below the body of the gun and within the circle of the trigger guard to permit the arm to lie flat along the side of the trigger. A lip 13 at the lower extremity of the arm 11 is bent at right angles to the plane of the arm 11 to overlie the front of, and to apply pressure to, the trigger 9 at the tip. The forward portion of the base has a tongue struck out and split to form an upstanding ear 14 and a rearwardly extending lug 15 passing over the edge of the trigger actuating plate to prevent the plate from moving out of its normal plane of movement.

A second plate 17 is pivoted to the trigger actuating plate 8 by means of pin 18. A portion of plate 17 is bent upward and over the plate, as at 19, and a shaft 20 extends from the arm 19 to the plate 17 and carries an irregular shaped fulcrum cam 21. The irregularities of the cam have been greatly exaggerated in the drawings to graphically illustrate the principle of the invention, but, as a matter of fact, the cam will be much more nearly round and the depressions very slight.

Trigger actuating plate 8 has an opening 22 through which a stud 23 passes. Stud 23 is carried by the case base plate and forms a pivot for an auxiliary trigger 24. The lower end of trigger 24 passes through the opening 41 and is offset laterally, as at 25, to position the finger piece 26 in substantially the same plane as the trigger 9. Trigger 24 has an arcuate portion 27 to fit around the fulcrum cam and a bearing point 28 to engage the cam when the trigger is actuated.

Upstanding lugs 29 and 30 on the trigger actuating plate 8 and second plate 17, respectively, form terminals to which are connected the opposite ends of the spring 31. Under ordinary circumstances, plates 8 and 17 act together as a single unit, the spring 31 being of sufficient strength to hold the plate 17 against the stop 32 projecting upwardly from the plate 8.

Pivoted to the base plate of the case at 33 is a latch member 34 provided with a sloping shoulder 35 to cooperate with a shoulder 36 provided at the edge of lug 29, as will be hereinafter described. Latch 34 is biased by a spring 37 for movement in a clockwise direction. The latch is also provided with a cam face 38 cooperating with a nose 39 on the trigger 24 for returning the latch to its normal inoperative position.

A spring 40 connects the upstanding ear 14 to the trigger 24 to hold the trigger in its forward position. The spring is attached to the trigger 24 at such a position that the spring must be deflected from its straight line position in order to pass around and frictionally engage the fulcrum cam 21.

When the auxiliary trigger is actuated, it swings around its pivot 23 and the point 28 presses against the fulcrum cam 21 and forces the cam and the attached plate 17 downward. The spring 31 is of sufficient strength to maintain plates 17 and 8 in their relative positions so that they operate as a unitary member, and when plate 17 is forced downward plate 8 moves down around its pivot 7, causing the trigger 9 to move and so fire the gun. Trigger actuated plate 8 must move to a certain point in order to cause the trigger 9 to release. Stop screw 71 is adjusted to stop the movement of the plate when this point is reached. During its rearward movement, auxiliary trigger 24 has its bearing point 28 in contact with the fulcrum cam 21 and there is a rotating motion of the bearing point 28 upon the cam 21 as the plates move downward. As cam 21 has an irregular outline, the length of the stroke of the auxiliary trigger will vary depending upon the surface of the cam 21 contacted by bearing point 28. Spring 40 draws the auxiliary trigger forward until it strikes the end of opening 41. Therefore the auxiliary trigger always starts its stroke from a fixed point. The plate 8 has a positive limit at the end of its downward movement. The particular portion of cam 21 which strikes the trigger will determine the upward limit of movement of the plate. In this manner the amount of downward movement the plate will have will be varied. As the trigger moves the plate, its stroke is proportionately varied. If the face 28 contacts a high point in the cam, the trigger stroke will be relatively short, and if it contacts a low point on the cam, the trigger stroke will be proportionately increased. It is obvious that intermediate points will vary the stroke in accordance with their distance from the center of the cam.

As the trigger is drawn backward, the nose 39 on the upper portion of the trigger will leave the cam surface 38 of the latch, and the latch will be permitted to rotate under the influence of the spring 37 until its upper surface strikes the under side of the shoulder 36. As the trigger continues to move rearwardly rocking the plate 8, the shoulder 36 will move forward, freeing the shoulder 35 and permitting the latch to rise behind shoulder 36. As the shoulder 35 slopes, the rise is gradual and the latch becomes fully engaged just about the time the plate 8 has reached its limit of movement. The shoulder 35 will hold the plate in its downward position, preventing its return, at any point after its initial engagement, so that if the marksman should decide not to fire, the cam will have a new setting the next time the trigger is pulled.

The latch mechanism is provided to hold the plate downward while the auxiliary trigger returns to its position of rest under the influence of the spring 40. In this manner the auxiliary trigger is spaced from the fulcrum cam 21 during its return swing and the cam is free to be rotated by the frictional bearing of the convolutions of the contracting spring 40 against its periphery.

Fulcrum cam 21 is rotated a little in clockwise direction during the firing stroke by contact with the auxiliary trigger, and it will be obvious that during the firing stroke the frictional bearing of the trigger against the cam will prevent its opposite rotation by the spring 40. The cam will be moved by the spring on the return stroke when this pressure is released by means of the latch holding the plate in its downward position. Thus the cam will rotate in a clockwise direction only. This will not provide a positive drive to rotate the cam and it may be rotated more or less, depending upon the slippage between spring and cam and the length of stroke of the auxiliary trigger. This is true whether the gun is actually fired or not. This enhances the value of the device, as it renders the firing point even more indeterminate than would be the case if the cam were positively rotated through a set degree of arc each time the gun was fired. By this arrangement an infinite movement of settings is provided between the highest and lowest points of the cam.

Just before the auxiliary trigger 24 reaches the limit of its forward swing, the nose 39 contacts cam face 38 of the latch and rotates the latch in a counterclockwise direction, releasing the plate 8 and permitting it to return to its position of rest, which position is determined by the cam 21 striking the trigger bearing point 28. Spring 40 serves the triple function of returning the auxiliary trigger to its inoperative position, rotating the cam 21, and drawing the plates 8 and 17 back to their inoperative position. The two plates 8 and 17, as has been described, function as a single plate when all of the mechanism is in working order. If, however, the safety lock of the gun is on, the gun trigger 9 is immovable. If some means were not provided to compensate for this, actuation of the auxiliary trigger 24 might cause breaking or straining of mechanism. For this reason, two plates are provided pivoted as at 18 so that should the gun be locked or mechanism jammed, plate 17 may move downward in its usual manner, but plate 8 will remain stationary, the spring 31 lengthening to permit this movement. When the auxiliary trigger is released, the plate 17 will return to its former

position, which position is determined by the cam 21 abutting the trigger. Spring 31 has the additional function of providing smooth continuation of auxiliary trigger pull beyond firing point when the gun trigger has released, and its resistance has greatly lessened suddenly. The tension of spring 31 added to that of spring 40 will preserve a uniform pull.

This structure provides a longitudinal stroke through the limits of which the pressure is substantially uniform. The firing will take place at an indeterminate point in the stroke with nothing to indicate to the marksman when the firing is to take place and there is no sudden drop in the pull of the auxiliary trigger after gun has fired. The first indication he will have that the firing mechanism has been released will be the recoil and sound of the explosion. Any physical reaction or flinching which may then occur will not spoil the shot as the bullet has by that time left the gun.

If the mechanism should break, the user of the gun may still fire it by continuing the backward stroke of the auxiliary trigger until it contacts the face of trigger 9 and by actual pressure moves the gun trigger 9.

A slight modification of the above structure is shown in Figure 7, wherein a cam follower 42 is pivotally connected to the auxiliary trigger 24 as at 43 and provided with a downwardly extending arm 44 to which the end of the spring 40 is attached. The pull of spring 40 will keep the long arm 45 of the follower tight against the surface of the cam and the friction between the follower and the cam will cause the cam to rotate on the return stroke of the auxiliary trigger. Such a device as this would be used primarily in the gun of an expert, where even the almost imperceptible sound of the convolutions of the spring rubbing against the surface of the cam might give some indication as to when the firing point is about to be reached.

In Figure 8, the device is shown as applied to a revolver. A slightly modified mechanism must be supplied as the trigger action of a revolver is different from that of an automatic. Substantially the same movement of the trigger takes place to release the firing mechanism, but the trigger is moved forward when the gun is fired and then moves backward a considerable distance as the hammer is drawn back. This is a necessary movement involved in the rotation of the cylinder or to cock the hammer. Consequently, provision must be made in the attachment to permit the trigger to follow its regular cycle of movement. This is accomplished by forming the plate 8 in two sections 46 and 47, the two sections being locked for unitary movement when the gun is fired, by means of a latch 48. Latch 48 is pivotally connected to the main portion of plate 8 as at 49 and is biased towards latching position by means of a spring 50. The latch has a relatively short arm 51 extending at the opposite side of the pivot from the keeper, which lever is beveled at its upper edge for cooperation with a cam 52 fixed to pivot upon the auxiliary trigger 24. Cam 52 is held outward against a stop 53 by means of spring 54. When the auxiliary trigger is moved, cam 52 will slide over cam 55 of the latch, and as the latch is in position holding the two parts of the plate 8 together, the revolver trigger will be actuated and the gun fired. As the auxiliary trigger 24 returns to its position of rest, the cam 52, due to its frictional engagement with the cam face 55, will swing out-

ward around its pivot, thus preventing its passing the latch on its return without first moving the latch about its pivot. This will release the trigger section 47 of the plate 8 and allow the revolver trigger the freedom of movement necessary to follow its regular cycle as the gun is cocked.

As shown in Figures 9, 10 and 11, the present invention lends itself ideally to the use of remote firing control by instructors. The bottom 4 of the case may be extended slightly, as shown at 56, and provided with a substantially square opening 57, and the plate 8 may have a similar extension 58 and opening 59. The housing will also have to be dropped to provide opposite openings 60 which form bearings for a remote control rod 61. Rod 61 may be made in sections coupled together by flexible tubing 62, and carry at its end a metal control shaft 63. The control shaft has circular ends 64 to seat in the openings 60 in the housing when the rod has been inserted in place, and the rod is clamped in position by means of a knurled nut 65. An indicating arrow 66 is attached to the opposite end of the metal control rod and serves to show the position of the shaft in the casing. The central portion of the shaft is cut away, as at 67, leaving only a quadrant of the shaft as at 68. The central portion of the shaft passes through the openings 57 and 59 in the extensions 56 and 58, respectively, with the shaft bearing against the sides 69 and 70 of the opening 59. When the auxiliary trigger 24 is moved, only the plate 17 will move, as the central portion of the control rod 63 prevents movement of the trigger actuating plate 8. At such time as the instructor desires to fire the gun, the rod is rotated to move the portion 68 to the opposite side of the opening 59 and the contraction of the spring 31 will move the plate 8 and actuate the trigger to fire the gun.

It is to be understood that the invention is adaptable either to an attachment or as a part of the firearm. It is only necessary that the plate 8 be in operative connection with that part of the firearm's mechanism which releases the firing mechanism. When it is to be attached to a firearm, the firearm's trigger will be the firing mechanism release, necessitating the use of an auxiliary trigger, but when built into a firearm will be connected to only that portion of the trigger which is inside the firearm, the remainder of the trigger being eliminated.

Although certain specific, practical embodiments of the invention have been shown and described, it is to be understood that the inventive concept is capable of many adaptations and changes from the structure shown and the invention is to be limited only by the scope of the appended claims.

Having thus described my invention, what I claim is:

1. Trigger mechanism for firearms comprising, a trigger, firing mechanism release means, a member to operate said firing mechanism release means, and pivoted means having a perimeter which varies in distance from the pivot interposed between said trigger and said member for transmitting movement of said trigger to said member, said means being shiftable whereby the length of the trigger stroke is varied on successive operations of the trigger.

2. Trigger mechanism for firearms comprising, a trigger, firing mechanism release means, a member to operate said firing mechanism release means, a pivoted cam having a perimeter which

varies in distance from the pivot interposed between said trigger and said member for transmitting movement of said trigger to said member, and means to impositively rotate said cam each operation of the trigger whereby the length of the trigger stroke is varied on successive operations of the trigger.

3. Trigger mechanism for firearms comprising, a trigger, firing mechanism release means, a member to operate said firing mechanism release means, a pivoted cam of irregular outline having its periphery at varying distances from the pivot interposed between said trigger and said member for transmitting movement of said trigger to said member, and frictional means to impositively rotate said cam on each operation of the trigger, whereby the cam is rotated in indeterminate amounts and the length of the trigger stroke is varied on successive operations of the trigger.

4. Trigger mechanism for firearms comprising, a trigger, firing mechanism release means, a member to operate said firing mechanism release means, a pivoted cam of irregular outline having its periphery at varying distances from the pivot interposed between said trigger and said member for transmitting movement of said trigger to said member, and means to bias said trigger toward inoperative position, said means being in frictional engagement with the periphery of said cam to impositively rotate said cam in indeterminate amounts during each trigger stroke whereby the length of the trigger stroke is varied on successive operations of the trigger.

5. Trigger mechanism for firearms comprising, a trigger, firing mechanism release means, a member to operate said firing mechanism release means, a pivoted cam of irregular outline having its periphery at varying distances from the pivot interposed between said trigger and said member and in contact with said trigger for transmitting movement of said trigger to said member, means to bias said trigger toward inoperative position, said means being in frictional engagement with the periphery of said cam whereby the cam will be impositively rotated in indeterminate amounts during each stroke of the trigger, and means to hold the member in operative position during the return stroke of the trigger whereby the trigger will be removed from engagement with the cam to permit the cam to rotate freely.

6. Trigger mechanism for firearms comprising, a trigger, firing mechanism release means, a member to operate said firing mechanism release means, a second member pivoted to said first-mentioned member, yieldable means interconnecting said members to cause said members to operate in unison, a cam carried by said second member in contact with said trigger for transmitting movement of said trigger to said second member.

7. An attachment for firearms having a trigger comprising, a trigger actuating member adapted to contact said trigger, an auxiliary trigger, and pivoted means having its perimeter at varying distances from the pivot interposed between said auxiliary trigger and said trigger actuating member for transmitting movement of said auxiliary trigger to said trigger actuating member, said means being shiftable whereby the length of stroke of the auxiliary trigger is varied on successive operations of the auxiliary trigger.

8. An attachment for firearms having a trigger comprising, a trigger actuating member adapted to contact said trigger, an auxiliary trigger, a pivoted cam of irregular outline having its perim-

eter at varying distances from the pivot carried by said trigger actuating member for transmitting movement of said auxiliary trigger to said trigger actuating member, and means to impositively rotate said cam whereby the length of stroke of the auxiliary trigger is varied on successive operations of the auxiliary trigger.

9. Trigger mechanism for firearms comprising, a trigger, firing mechanism release means, an actuating member for said firing mechanism release means operable by said trigger, said actuating member comprising relatively movable sections, means to unite the sections for unitary movement when the firearm is to be fired, and means to release said uniting means after the firearm has been discharged to permit independent movement of the said sections.

10. Trigger mechanism for firearms comprising, a trigger, firing mechanism release means, an actuating member for said firing mechanism release means, a cam interposed between said trigger and said actuating member to transmit movement of said trigger to said actuating member, said actuating member comprising relatively movable sections, latch means to unite the sections for unitary movement when the firearm is to be fired, and means to release said latch after the firearm has been discharged to permit independent movement of the said sections.

11. Trigger mechanism for firearms comprising, a trigger, firing mechanism release means, an actuating member for said firing mechanism release means, a cam interposed between said trigger and actuating member to transmit move-

ment of said trigger to said actuating member, means to rotate said cam, said actuating member comprising relatively movable sections, latch means to unite the sections for unitary movement when the firearm is to be fired, and means to release said latch after the firearm has been discharged to permit independent movement of the said sections.

12. In trigger mechanism for firearms as claimed in claim 5, means carried by said trigger to release said member holding means as the trigger approaches its position of rest.

13. Trigger mechanism for firearms comprising, a trigger, firing mechanism release means, a member to operate said firing mechanism release means, a pivoted cam of irregular outline interposed between said trigger and said member for transmitting movement of said trigger to said member, means to bias said trigger toward inoperative position, a link interposed between said trigger and said biasing means frictionally contacting said cam and urged toward said cam by said biasing means for impositively rotating the cam in indeterminate amounts during each stroke of the trigger.

14. In trigger mechanism for firearms as claimed in claim 6, remote control means comprising, a rod rotatably connected to said firearm, and a cam carried by said rod to engage said first-mentioned member to prevent its movement when the cam carried by the rod is in one position and to release the member when the rod is rotated.

PAUL PALE.
